PROCESS AND APPARATUS FOR GRINDING GLASS

Filed Feb. 14, 1931

UNITED STATES PATENT OFFICE

THOMAS H. SWARTZLANDER, OF ASPINWALL, PENNSYLVANIA, ASSIGNOR TO PITTSBURGH PLATE GLASS COMPANY, A CORPORATION OF PENNSYLVANIA

PROCESS AND APPARATUS FOR GRINDING GLASS

Application filed February 14, 1931. Serial No. 515,757.

The invention relates to glass grinding and particularly to that part of the system which has to do with the rough grinding. In apparatus of this kind, the grinding sand is supplied to a grading cone which distributes it to the various grinding machines. The used abrasive and water drains into a return trough which carries it back to a supply sump. From this point the mixture is pumped back into the grading cone and any sand coarse enough for rough grinding is again circulated to the rough grinders and reused. The finer grades of sand in the cone are carried to other grinding machines following the rough grinders. New sand is added to the system from time to time in order to take the place of the coarse material which is reduced to the finer grades in the rough grinding operation. The abrasive is thus used over and over, thus reducing the quantity of sand required to a minimum. It is difficult to exclude from the new sand all material which is too coarse for use, such as small pebbles (called shot) and the like, and once introduced in the circulation system, they continue to circulate repeatedly past the grinders and cause damage by scratching. Other objectionable material may also get into the system and be recirculated, such as chips of glass, lumps of plaster, small pieces of iron, and the like, and in the course of time a considerable body of the objectionable material accumulates in the system. The purpose of the present invention is to provide a simple, convenient auxiliary separating means through which the circulating material may be passed at suitable intervals in order to clear the system of oversize particles of material of all kinds. One embodiment of the invention is shown in the accompanying drawing, wherein:

The figure is a partial side elevation and partial vertical section showing the application of the apparatus to the rough grinding end of a straight away grinding system.

The grinding system to which the invention is applied may be of any desired type, the portion of the system shown comprising a series of tables 1, above which are placed a series of driven grinding runners 2, 3, 4, etc., such runners comprising the rough grinding

portion of the system. The cars or tables 1 are mounted upon a track 5 and carried slowly beneath the grinding runners by any suitable driving mechanism. A grading cone 6 supplies the abrasive and water for the rough grinding operation, a pipe 7 leading from the lower portion of the cone and discharging into the distributing box 8 from which the pipes 9, 9, 9, etc. lead to the various grinding runners. The drainage from the runners comprises a mixture of water and used abrasive and drains into the trough 9^a and is conducted through the pipe 10 to another trough 11 leading to the sump 12. A centrifugal pump 13 supplies the mixture of sand and water in the sump 12 to the lower end of the cone 6 through the pipe 14. This provides an upward flow of liquid through the grading cone, thus grading the material with the coarsest grades at the bottom of the cone and the finer grades thereabove. The coarser grades which pass out through the pipe 7 are used with the rough grinders 2, 3, 4, etc., while the other grades are removed from the cone by means of suitable piping (not shown) and used with those grinders following the rough grinders. The system as just described is well known in the art and provides a means for circulating the abrasive and water to the grinding machines and then returning it, thus forming a continuous cycle.

Located below the level of the grinding system is a separator in the form of a vertical tank 15 to the lower portion of which water may be supplied under pressure from the main 16. This is preferably accomplished by means of a plurality of small pipes 17 leading from the manifold 18 which is connected to the main 16, into the bottom of the tank. This tank has around its upper portion a trough 18^a for receiving the overflow from the tank and such trough is connected by means of the pipe 19 with the troughs 11 leading into the sump 12. Located intermediate the ends of the tank 15 is an outlet pipe 20 leading to the sump 21 which discharges to the sewer. Seated upon the upper end of the tank 15 is a box 22 for receiving a mixture of abrasive and water from the trough 9^a when the valve 23 in the pipe 24

is open. The box is provided with a transverse baffle 25 and with a discharge pipe 26 leading through the bottom of the box into the tank 15. A valve 27 operated from the shaft 28 serves to control the flow from the box to the tank beneath.

The separator as above described constitutes a means for separating from the mixture of abrasive and water circulating through the system the material which is unsuitable for use in grinding because of its size, such as small pebbles, pieces of plaster, chips of glass and the like. When it is desired to cleanse the system of this material, the valve 29 in the pipe 10 is closed and the valve 23 in the pipe 24 is opened so that the return circulation from the trough 9 passes down into the separating apparatus. At this time the valve 30 in the main 16 is open so that a grading flow of water is provided upward through the tank 15. This flow is so regulated that the finer material suitable for use in the grading system is washed up over the top of the tank and returns to the trough 11 through the trough 18^a and pipe 19. The material which is too coarse for use accumulates in the bottom of the tank and may be withdrawn continuously or from time to time through the pipe 20 which is provided with a valve 31. If desired, the separator might be kept continuously in the circulation, but preferably it is operated only at intervals of a day or so for a short time. At other times, the valve 23 is closed and the valve 29 is opened so that the circulation of abrasive and water is cut off from the separator.

The foregoing arrangement provides for a by-pass of the sand and water through the separator on the return side of the grinding apparatus. Under these conditions, the separator can be used without interference with the grinding operation. In some cases, it is desirable to use the separator when the grinders are not operating and provision is made for accomplishing this by providing a by-pass through the separator on the inlet side of the grinders. The apparatus for doing this comprises a box 32 and a pipe 33 leading from such box down into the separator box 22. The lower end 34 of the pipe 7 is of flexible material and when it is desired to use the separator, the pipe 34 is switched to the dotted line position shown in Fig. 1 in which it discharges into the box 32. The separator can thus be used to clean out the coarse material from the system when the grinders are not in use. In carrying out this latter operation, the pump 13 may be operated at an increased speed so that all the coarse material which collects in the lower end of the cone 6 will be carried up through the pipe 7 due to the high velocity produced in this pipe. In this manner all of the coarse material in the cone or in the other parts of the system can be withdrawn in a short period

of time and sent through the separator preliminary to the operation of the grinding apparatus. It will be understood that the invention is not limited to the use of the particular separator shown, as any separator suitable for the purpose may be employed. Also that the invention is not limited to the use of a separator with the particular grinding apparatus shown and described. In its broad form, the invention comprehends the use of any separator with any type of grinding system having a continuous circulation where the separator is arranged where it can be switched in and out of the circulation at will in order to remove oversize and foreign material which tend to injure the glass.

In the normal operation of the apparatus, mud and other light material too fine for use is conducted from the overflow trough 35 around the top of the grading cone to the sewer 21 by means of the pipe 36. This pipe is provided with a valve 37 and a connection 38 leading into the sump 12 also provided with a valve 39. A connection 40 provided with a valve 43 leads from the pipe 14 to the box 22 and valves 41 and 42 are provided in the pipe 14 above and below the pipe 40. This provides still another alternative method of operation, and prevents a loss of sand when the pump 13 is run at a higher speed than normal in order to lift the coarse material from the bottom of the cone when the end of the pipe 34 discharges into the box 8 as heretofore described. At such time, a quantity of usable sand discharges over the upper edge of the cone 5 into the trough 35 and would be lost into the sewer unless provision were made to save it. This is accomplished by closing the valve 37 and opening the valve 39 so that the overflow from the cone flows through the pipes 36 and 38 to the sump 12. It is also possible to withdraw the contents of the cone by gravity to the separator box 22, when the pump 13 is not running, by closing the valve 42 and opening the valve 43. The operation of the separator during this gravity withdrawal eliminates the oversize material as heretofore described, while the usable grades of sand are returned to the sump 12. Under normal operating conditions, the valve 43 is closed.

What I claim is:

1. The combination with grinding apparatus, of a grading system therefor comprising a grading cone, means for continuously circulating a mixture of abrasive and water in a circuit from the cone to the grinding means and then back to the cone, a separating tank adjacent the line of travel of the circulating mixture, connections whereby said tank may be switched at will into and out of the line of travel of the circulating mixture of abrasive and water so that said mixture passes therethrough, means supplying an upward flow of water through the

separating tank for separating from the abrasive suitable for use oversize material unsuitable for use, and an outlet leading from the lower portion of the tank for permitting the discharge to waste from the tank of some of the water therein together with said oversize material.

2. The combination with grinding apparatus, of a grading system therefore comprising a grading cone, means for continuously circulating a mixture of abrasive and water in a circuit from the cone to the grinding means and then back to the cone, a separating tank adjacent the line of travel of the circulating mixture, connections whereby the return circulation from the grinding apparatus to the cone may be switched at will through said tank so that said mixture passes therethrough, means supplying an upward flow of water through the separating tank for separating from the abrasive suitable for use oversize material unsuitable for use, and an outlet leading from the lower portion of the tank for permitting the discharge to waste from the tank of some of the water therein together with said oversize material.

3. The combination with grinding apparatus, of a grading system therefore comprising a grading cone, means for continuously circulating a mixture of abrasive and water in a circuit from the cone to the grinding means and then back to the cone, a separating tank adjacent the line of travel of the circulating mixture, connections whereby the circulation of the mixture may be diverted at will from the grinding apparatus and sent through said tank, means supplying an upward flow of water through the separating tank for separating from the abrasive suitable for use oversize material unsuitable for use, and an outlet leading from the lower portion of the tank for permitting the discharge to waste from the tank of some of the water therein together with said oversize material.

4. The combination with grinding apparatus, of a grading system therefore comprising a grading cone, means for continuously circulating a mixture of abrasive and water in a circuit from the cone to the grinding means and then back to the cone, a separating tank adjacent the line of travel of the circulating mixture, connections whereby the circulation of the mixture to the grinding apparatus may be by-passed at will through said tank and whereby the return circulation from the grinding apparatus may be directed through said tank, means supplying an upward flow of water through the separating tank for separating from the abrasive suitable for use oversize material unsuitable for use, and an outlet leading from the lower portion of the tank for permitting the discharge to waste from the tank of some of the water therein together with said oversize material.

5. A process for use in connection with glass grinding apparatus requiring finely divided abrasive and water, which consists in grading the material in a body of water by an upward flow of water therethrough, circulating the mixture to the grinding apparatus, collecting the mixture draining from the apparatus and returning it to said body of liquid in a continuous cycle, and at intervals by-passing the circulating mixture through a separator and removing therefrom any oversize and foreign material unsuitable as abrasive and liable to injure the glass.

6. A process for use in connection with glass grinding apparatus requiring finely divided abrasive and water, which consists in grading the material in a body of water by an upward flow of water therethrough, circulating the mixture to the grinding apparatus, collecting the mixture draining from the apparatus and returning it to said body of liquid in a continuous cycle, and at intervals by-passing the circulating mixture around the grinding apparatus so as to send the mixture through a separator instead of to the grinding apparatus, and in such separator removing from the mixture any oversize and foreign material unsuitable as abrasive and liable to injure the glass.

7. A process for use in connection with glass grinding apparatus requiring finely divided abrasive and water, which consists in grading the material in a body of water by an upward flow of water therethrough, circulating the mixture to the grinding apparatus, collecting the mixture draining from the apparatus and returning it to said body of liquid in a continuous cycle, and at intervals by-passing the circulating mixture which drains from the grinding apparatus through a separator and removing therefrom any oversize and foreign material unsuitable as abrasive and liable to injure the glass.

In testimony whereof, I have hereunto subscribed my name this 2nd day of February, 1931.

THOMAS H. SWARTZLANDER.
